SAFETY RAZOR AND SAFETY RAZOR BLADE

Aaron Samuelson, New York, N. Y.

Application November 27, 1935, Serial No. 51,725

2 Claims. (Cl. 30—48)

My invention relates to a new and improved safety razor, and to a new and improved safety razor blade.

One of the objects of my invention is to provide a safety razor, in which the cutting edge of the blade will be relatively free and unobstructed.

Another object of my invention is to provide a safety razor in which the cutting edge of the blade is held inclined to what may be termed the vertical axis of the holder, so that a true cutting action is secured, instead of a scraping action.

Another object of my invention is to improve that type of razor which is generally known as the "Gillette" razor, and also to improve the type of blade which is used in said type of razor.

Other objects of my invention will be set forth in the following description and drawing which illustrate a preferred embodiment thereof, it being understood that the above statements of the objects of my invention is intended to generally explain the same without limiting it in any manner.

Fig. 1 is a side elevation of the improved razor. Fig. 2 is a vertical central section taken through Fig. 1, the handle of the razor being shown partially in elevation.

Fig. 3 is a sectional view on the line 3—3 of Fig. 2.

Fig. 4 is a sectional view on the line 4—4 of Fig. 2.

Fig. 5 is a side elevation showing the blade and the accessory plates or parts.

Heretofore, in razors of the "Gillette" type, it has been customary to bend the thin and bendable blade, so that the cutting edges of the said blade either abutted or were very close to the edges of the guard. Said guard had a series of teeth, and the configuration of the razor blade interfered with the free cutting action thereof, along the entire edge or edges of said blade.

Likewise, in razors of this type, in which it is customary to move the razor up and down, the blade cuts the hair by a scraping action, instead of using the true diagonal stroke, which is used by professional barbers.

According to the improved invention, a number of the parts may be of conventional type.

For example the drawing illustrates a razor having a clamping plate or top member 1, and a guard or bottom member 2. Said bottom member 2 is provided with the usual spaced guard teeth.

The top member 1 is provided with the usual externally threaded shank 3, which can be en-

gaged by the internally threaded wall of a recess which is provided in the upper end of the handle H.

The razor blade 6 is made of thin steel, so that it has little or no inherent rigidity.

Said blade 6 is provided with the usual opening or slot, through which the shank 3 may pass.

In this particular embodiment, the upper member 1 is provided with a rib R which passes through the slot of the blade 6, and which enters a corresponding recess which is formed in the lower member 2.

A plate 4 is located between the blade 6 and the bottom surface of the upper member 1, and a plate 5 is located between the bottom surface of the blade 6, and the upper or inner surface of the member 2.

The rib R projects through slots 7 and 8 which are formed respectively in said supplemental plates 4 and 5.

Said plates 4 and 5 can be formed of bendable metal or other suitable bendable material. Said plates 4 and 5 may be formed from resilient material, or from non-resilient material.

As shown in the drawing, said plates 4 and 5 are tapered longitudinally, or along a direction which is perpendicular to the central axis of the holder H, and which is parallel to the plate of the paper in Fig. 5.

As shown in the drawing, the thin edge 4a of the plate 4 is directly above the thick edge 5a of the plate 5. The thick edge 4b of the plate 4, is above the thin edge 5b of the plate 5.

Hence, when both said plates are assembled in the holder and with the blade 6 between them, the assembly of said plates is of substantially equal thickness at both ends of said assembly.

The adjacent surfaces of said plates 4 and 5 are inclined to the vertical central axis of the holder, namely, the central vertical axis of the holder H. For convenience, the device is described with the holder located so that the handle H is vertical, although the device may be used in any position.

By means of such assembly the cutting edges of the blade 6 are held inclined to the vertical axis of the holder. When the blade is used in the holder, said blade is bent transversely, so that it has uniform transverse curvature throughout. The cutting edges of said blades are straight and said straight edges are inclined to the vertical axis of the razor. Considering Fig. 5, if the blade 6 were integral with plates 4 and 5 and said plates and blade were in planar form, the cutting edges of the blade would be

inclined to the opposed planar faces of the assembled parts, namely, the top face of plate 4 and the bottom face of plate 5. As stated previously, members 4 and 5 could be integral with blade 6 and said plates can be resilient, so as to form a resilient razor blade having the desired configuration, which can be used directly in an ordinary razor of the "Gillette" type. For convenience the direction which is parallel to the rib R can be designated as the longitudinal direction.

Hence, when the holder is moved downwardly in the usual manner, the cutting edges of the blade are at an angle to the direction of movement of the holder.

Said angle may be made as large or as small as is desired.

Likewise the cutting edge of the blade is spaced from the guard teeth, so as to provide unobstructed cutting action. However, it would not be departing from the invention if the cutting edge or edges of the blade were close to the edges of the guard, since the essential feature is the diagonal cutting effect above mentioned.

Instead of using separate plates 4 and 5, said plates could be connected to, or they could be integral with the members 1 and 2.

Likewise said plates 4 and 5 could be connected to, or they could be integral with the blade 6.

One of said plates 4 or 5 could be connected to, or could be made integral with, the corresponding member of the holder, or with the blade 6.

The invention also applies to blades having a single cutting edge, although it has been illustrated specifically in connection with blades having two cutting edges.

I do not wish to be limited to the specific means shown for holding the blade so that its edges will be in said diagonal relationship.

I have shown a preferred embodiment of my

invention but numerous changes and omissions could be made without departing from its spirit.

For example, the invention may be utilized by having a holder of the conventional type, and having the axis of the handle or holding part H, inclined to the clamping parts of the razor, instead of being perpendicular to said clamping parts.

The natural tendency will be then to move the razor in a direction parallel to the axis of the holding part H, thus securing said diagonal stroke.

However the construction illustrated more specifically is preferable, since it permits the parts to be made and attached in the ordinary manner, and the razor can be moved vertically, while securing the correct diagonal cutting stroke.

Likewise, the body of the blade is held rigid, save for the cutting edge portions thereof, which are not clamped, so that said cutting edge portions are flexible and can yield upwardly and downwardly relative to the members 1 and 2.

I claim:

1. A safety razor comprising superposed longitudinally tapered members adapted to hold a blade between them, said members having surfaces adapted to abut the blade, said surfaces being inclined to the axis of the holding part of the razor.

2. A safety razor comprising superposed members and means adapted to force said superposed members towards each other so as to clamp a blade between said superposed members, plates located between said superposed members and having the blade located between them, said plates being longitudinally tapered, so that each said plate has a thick end and a thin end, the thin end of one plate being adjacent the thick end of the upper plate.
